FIG. 1

FIG. 2

INVENTOR
Arthur W. Wadsworth
By James N. Ramsey
ATTORNEY

UNITED STATES PATENT OFFICE.

ARTHUR W. WADSWORTH, OF FORT THOMAS, KENTUCKY, ASSIGNOR TO THE WADSWORTH WATCH CASE COMPANY, OF DAYTON, KENTUCKY, A CORPORATION OF KENTUCKY.

DESIGN FOR A WATCHCASE.

56,787.

Specification for Design.

Patented Dec. 14, 1920.

Application filed July 10, 1920. Serial No. 395,391. Term of patent 14 years.

To all whom it may concern:

Be it known that I, ARTHUR W. WADSWORTH, a citizen of the United States, residing at Fort Thomas, in the county of Campbell, and in the State of Kentucky, have invented a new, original, and ornamental Design for a Watchcase, of which the following is a specification, reference being had to the accompanying drawing, forming part thereof.

In the drawing:

Figure 1 is a side elevation of the watch case and

Fig. 2 is an edge view thereof.

I claim:

The ornamental design for a watchcase, substantially as shown.

ARTHUR W. WADSWORTH.

Witnesses:

JAMES N. RAMSEY,
GLADYS L. HORTON.
